UNITED STATES PATENT OFFICE

142,670

DESIGN FOR A BOOK OR ARTICLE OF SIMILAR NATURE

Wilfred Rogow, Bayonne, N. J.

Application June 14, 1945, Serial No. 120,104

Term of patent 7 years

(Cl. D6—2)

To all whom it may concern:

Be it known that I, Wilfred Rogow, a citizen of the United States, residing at Bayonne, county of Hudson, and State of New Jersey, have invented a new, original, and ornamental Design for a Book or Article of Similar Nature, of which the following is a specification, reference being had to the accompanying drawing, forming a part thereof.

Fig. 1 is a front view of a book showing my new design. The rear view is similar to the front view.

Fig. 2 is an edge view thereof.

I claim:

The ornamental design for a book or article of similar nature, as shown and described.

WILFRED ROGOW.
